[57] CLAIM

The ornamental design for a tray floor construction, as shown and described.

DESCRIPTION

FIG. 1 is a perspective view of a tray floor construction showing my new design;

FIG. 2 is a top plan view thereof;

FIG. 3 is a bottom plan view thereof;

FIG. 4 is a front elevational view thereof; the rear elevational view being a mirror image thereof; and,

FIG. 5 is a left side elevational view thereof; the right side elevational view being a mirror image thereof.

The broken line showing of a tray wall structure in FIGS. 1-5 is for an environmental purposes only and forms no part of the claim.

FIG. 1

FIG. 2

FIG. 3

FIG. 4

FIG. 5
